UNITED STATES PATENT OFFICE.

THOMAS E. NIBLOCK, OF GREAT FALLS, MONTANA.

AUTOMATIC CONTROL OF ELECTRICAL FURNACES.

Application filed February 8, 1921. Serial No. 443,419.

To all whom it may concern:

Be it known that I, THOMAS E. NIBLOCK, a citizen of the United States, residing at Great Falls, in the county of Cascade and 5 State of Montana, have invented certain new and useful Improvements in Automatic Controls of Electrical Furnaces, of which the following is a specification.

This invention relates to an automatic control of electrical furnaces and more particularly to that type of furnaces in which the electrodes are raised and lowered by means of an electrically driven winch.

This invention is primarily intended for 15 controlling and regulating the lowering of electrodes into a charge of high electrical resistance.

The objects and the operation of the invention will appear more clearly from the 20 specification and the drawings forming part of it.

In the drawing Fig. 1 is a more or less diagrammatic view of an arrangement embodying the invention; and Fig. 2 is a fragmentary plan view of a detail.

In the drawings 1 is a furnace and 2 the electrodes supported by chains 3 above the furnace. Upon a suitable supporting frame 4 is mounted the winch 5 and the electric motor 6 driving the latter. The chains 3 pass over pulleys 7 and around sheaves 8 and have their ends connected to the frame 4. It is understood, however, that the particular form of support of the electrodes upon the 25 chains is not material to the invention.

In the arrangement illustrated the electrodes are to be so positioned in relation to the charge in the furnace that a certain potential difference exists between them and 40 the carbon bed of the furnace or ground or neutral. Consequently the electrodes are to be successively lowered to maintain this potential difference during the operation of the furnace.

In order to control the movement of the electrodes I provide between the electrodes 45 and the bed of the furnace a circuit including current-responsive means for indicating the potential difference. As indicated, the circuit starts from the electrode holder 9, includes a rheostat 10, a solenoid 11 and terminates at the terminal 12 connected to the carbon bed.

The solenoid 11 acts upon a plunger 13 50 suspended from a beam 14, the beam being supported upon a fulcrum 15. The beam

carries contact pieces 16 and 17 adapted to contact with stationary contacts 18 and 19 respectively. Contact pieces 18 and 19 are separately connected to one side of a low voltage direct current busbar 27 through solenoids 20 and 21. Solenoid 20 actuates a plunger 22 which is operatively connected to a double pole switch 25, while solenoid 21 actuates a plunger 23 connected to a similar 65 switch 26. A connection 24 leads from the other side of the busbar to the fulcrum of the beam 14. The switches 25 and 26 and the armature of the motor 6 are so interconnected that when one switch is closed current 70 passes through the armature of the motor in one direction and when the other switch is closed, current passes through motor in opposite direction.

The mechanism so far described operates 75 as follows:

So long as the potential between the holder 9 and the terminal 12 is normal, the current passing through the solenoid 11 and acting on the plunger 13 is just sufficient to hold the 80 beam 14 in balanced position between the contacts 18 and 19. Should the potential between holder 9 and terminal 12 rise, however, an increased current will flow through the solenoid 11, causing a lifting of the plunger 85 and a swinging of a beam 14 whereby contact is established between contact piece 16 and contact 18. Thereby the circuit through solenoid 20 is closed and the plunger 22 is actuated closing switch 25. Thereupon the 90 current from busbar 27 flows through the armature of the motor in such a direction that the motor turns in a direction to lower the electrodes into the charge. Ordinarily this lowering movement would continue until 95 the potential reaches the normal value whereupon the action of the solenoid 11 would again be balanced by the weight of the plunger 13 to bring the beam 14 into neutral position between the contacts 18 100 and 19.

If, as it often happens, there should be some internal furnace disturbance and a charge of high resistance is shifted into the path of the current flowing from the electrode, the potential difference between the electrode and ground or neutral becomes high, causing a lowering of the electrode, as above pointed out, until the potential is again normal.

Should the charge beneath the electrode become of high resistance and of sufficient

hardness, to prevent the further lowering of the electrodes, the motor will continue to operate thus completely unwinding the cable or chain by which the electrodes are suspended, often burning the cables or chains and allowing the electrodes to tip over and causing a short circuit or sometimes breaking the carbon electrode.

To prevent such a possibility and to automatically operate upon the obstructing mass or body to disintegrate it I have provided the following means constituting the invention.

A lever 28 is pivotally supported upon a standard 29 so as to have a relatively long arm extending to one side of the fulcrum and a relatively short arm extending to the other side. The short arm has a counter weight 37 to slightly overbalance the long arm. The arrangement is such that the plane of movement of the lever or of a part thereof intersects the plane of travel of the cable or chain. As indicated in Fig. 2 the long arm carries at its end a cross arm 30 disposed in the path of the chain when it sags.

In the circuit between the electrode holder 9 and the terminal 12 I have inserted a switch 31 which may be opened directly or indirectly as a result of the movement of the lever 28 when the latter is acted upon by the sagging cable or chain. The particular form of the switch, the form of the lever and the relationship of the parts involved is not material provided they operate to open the circuit including the solenoid 11 when the chain sags. For the purpose of illustration I have shown in the circuit a horizontal gap defined by the terminals 32 and 33 and a bridging piece 34 carried at the end of a resilient arm 35 which may be conveniently supported upon the standard 29, the arm 35 being normally under sufficient tension to force the bridging piece 34 upon the terminals 32 and 33 to close the gap. At the end of the short arm is mounted a pin or hammer 36 positioned to strike against the bridging piece 34 and lift it out of contact with the said terminals when the sagging chain depresses the long arm and thereby causes a rise of the short arm.

The operative significance of the arrangement just described is as follows:

If the electrodes should meet in their downward movement a mass or body of sufficient hardness to prevent the farther lowering of the electrodes and at the same time of high resistance to cause a high potential drop between electrode and ground or neutral, the motor will operate in a direction to lower the electrodes but since the movement of the electrodes is arrested, the chains will slacken and sag. The weight of the chains thus will bear upon the long arm of the lever and depress while the short arm rises causing the

switch 31 to open. The solenoid 11 will be de-energized allowing the plunger 13 to drop whereby the beam 14 is actuated to close the circuit through solenoid 21 causing the closing of switch 26 and the reversing 70 of the motor. The chains will thus be pulled taut again and the counterweight 37 will cause the turning of the lever 28 and the closing of the switch 31, re-energizing solenoid 11 and raising plunger 13. Thus, so 75 long as the obstruction of high resistance intercepts the further downward movement of the electrodes, the chains will be alternately pulled taut, slightly raising the electrode away from the charge, causing an arc, the 80 intense heat of which will tend to burn and soften the obstructing mass, and slackened causing a hammer action of the electrode upon the obstructing body tending to disintegrate it or to sufficiently agitate the charge 85 to move the obstructing body out of the path of the electrodes.

In this manner, the overrunning of the chain is prevented and in addition the electrodes are operated to automatically adjust 90 the conditions in the furnace to normal conditions after a disturbance is caused in the manner mentioned.

In the foregoing I have referred to the potential difference between the electrodes 95 and ground or neutral as the governing factor in the operation. It is understood that the particular arrangement including the automatic control switch 31 may find equal application in connection with means responsive to the rate of current flow through the electrodes. In other words the current actuating electro-magnetic means such as solenoid 11 and plunger 13 may be derived, as is well understood, from a current transformer connected to the circuit feeding the electrodes, although the arrangement would have to be slightly modified in some minor detail to bring about the proper operation of the motor. 100

While I consider the arrangement disclosed as a preferred embodiment of the invention, I am fully aware that it may be carried out in various other ways.

Thus the use of a winch and chain is particularly adapted for slightly raising the electrode away from the charge, causing an arc, the intense heat of which will tend to burn and soften the obstructing mass and imparting a hammer action to the electrodes, 120 but the idea of imparting such action may be executed in connection with other provisions for raising and lowering the electrodes.

In the preferred embodiment I use a chain so disposed that a portion thereof has a more 125 or less horizontal position to cause a sagging when the tension is released. Within the scope of the invention, however, the change of tension may be translated under different conditions and by different means to cause 130

the operation of the switch 31 or its equivalent.

In the claims the term "chain" is intended to cover any flexible suspension means in the nature of a chain or cable.

I claim:

1. In a system for automatically controlling the movement of electrodes in an electric furnace, the combination with means responsive to electrical conditions in the furnace to adjust the position of an electrode in the furnace, of means operative when the downward movement of the electrode is obstructed to slightly raise the electrode causing an arc and to return the electrode with a hammer action.

2. In a system for automatically controlling the movement of electrodes in an electric furnace, the combination with means responsive to electrical conditions in the furnace to adjust the position of an electrode in the furnace, of means operative when the downward movement of the electrode is obstructed to alternately raise and lower the electrode to cause successive impacts of the electrode upon the charge in the furnace.

3. In a system for automatically controlling the movement of electrodes in an electric furnace, the combination with an electrode, means for movably suspending the electrode, means for raising and lowering the electrode, means responsive to electrical conditions in the furnace for controlling the movement of the electrode and means responsive to the tension in the line of suspension of the electrode for causing an alternate raising and lowering of the electrode when the downward movement of the electrode is obstructed.

4. In a system for automatically controlling the movement of electrodes in an electric furnace, the combination of an electrode, a chain for movably suspending it, means responsive to electrical conditions in the furnace for controlling the movement of the electrode and means responsive to the tension in the chain for causing an alternate raising and lowering of the electrode when the downward movement of the electrode is obstructed.

5. In a system for automatically controlling the movement of electrodes in an electric furnace, the combination of an electrode, a chain for movably suspending it, said chain having a portion disposed in a substantially horizontal plane, means responsive to electric conditions in the furnace for controlling the movement of the electrode, and means responsive to the tension in the chain for causing an alternate raising and lowering of the electrode when the downward movement of the electrode is obstructed.

6. In a system for causing an alternate raising and lowering of the electrode when the

downward movement of the electrode is obstructed, said last mentioned means including an element supported below the said horizontal portion for movement in a vertical plane, switch mechanism and means for translating movement of said element to the switch mechanism.

65 7. In a system for automatically controlling the movement of electrodes in an electric furnace, the combination of an electrode, a chain for movably suspending it, said chain having a portion disposed in a substantially horizontal plane, means responsive to electric conditions in the furnace for controlling the movement of the electrode, and means responsive to the tension in the chain for causing an alternate raising and lowering of the electrode when the downward movement of the electrode is obstructed, said last mentioned means including a lever pivotally supported intermediate its ends and having a part disposed in the plane of movement of and below said horizontal chain portion, means on the lever 80 tending to force the said part to an upper position, a switch and means operative to close the switch when said part is in its upper position and to open the switch when it is in a lower position.

85 8. In a system for automatically controlling the movement of electrodes in an electric furnace, the combination of an electrode, a chain for movably suspending it, said chain having a portion disposed in a substantially horizontal plane, a lever pivotally supported intermediate its ends, one end of said lever intersecting the vertical plane of motion of the chain, a weight on the other end of the lever tending to force the said 90 first end to an upper position, a switch mechanism and means on the lever for opening the switch when said first end is moved away from its upper position.

95 100 9. In a system for automatically controlling the movement of electrodes in an electric furnace, the combination of an electrode, a chain for suspending the electrode, said chain having a portion disposed in a substantially horizontal plane, means connected 105 with the chain for raising and lowering the electrode and means for controlling said means, said controlling means including an element yieldingly disposed in the plane of and below the horizontal portion of the 110 chain and adapted to be depressed by the sagging of the chain and means for translating the movement of the element.

115 In testimony whereof, I affix my signature.

THOMAS E. NIBLOCK.
